PANTS HANGER

Leon H. Zeuthen, Minneapolis, Minn.

Application December 26, 1939, Serial No. 310,867

1 Claim. (Cl. 223—95)

My invention relates to improvements in pants hangers.

The object of this invention is to provide an extremely simple and highly efficient pants hanger which is easy to apply in the open bottoms of the legs of a pair of pants, which will securely hold a pair of pants suspended therefrom in their full length, without creasing or wrinkling the same, and which is of comparatively small cost to manufacture.

To the above end, generally stated, the invention consists of the novel construction and arrangement of parts hereinafter described and defined in the claim.

In the accompanying drawing, which illustrates the invention, like characters indicate like parts throughout the several views.

Referring to the drawing:

Fig. 1 is a side elevation of the improved pants hanger, some parts being shown in different positions by means of broken lines, and also showing, fragmentarily and diagrammatically in section by means of broken lines, a pair of pants held suspended by said hanger;

Figure 2 is a plan view of the parts shown in Fig. 1;

Fig. 3 is a left-hand elevation of the parts shown in Fig. 1;

Fig. 4 is a detail view principally in elevation of the left-hand pair of prongs, and also showing the friction members in section;

Fig. 5 is a fragmentary detail view principally in elevation of the left-hand pair of prongs, with some parts sectioned on the irregular line 5—5 of Fig. 4;

Fig. 6 is a detail view in side elevation of the right-hand prong, as shown in Fig. 4;

Fig. 7 is a detail view principally in elevation of the right-hand pair of prongs, with some parts sectioned on the irregular line 7—7 of Fig. 1;

Fig. 8 is a detail view principally in elevation, with some parts sectioned on the irregular line 8—8 of Fig. 7;

Fig. 9 is a detail view in elevation of the right-hand prong, as shown in Fig. 7; and

Fig. 10 is a detail view with some parts sectioned on the line 10—10 of Fig. 1.

It is thought that the invention will be best understood by describing the method of forming the improved pants hanger from a single piece of spring wire. First, this wire is folded, at its longitudinal center, upon itself transversely of the plane of the hanger and then bent to form a relatively large hook 11 that lies in the plane of the hanger. Second, the two parallel sections

of the wire forming the shank 12 of the hook 11 are connected by a longitudinally split sleeve 13 folded therearound. Third, the two end portions of the wire are twisted, at the lower end of the sleeve 13, into the plane of the hanger and then bent downwardly into diverging relation to afford a pair of upright members 14. These members 14, as shown, are bent at their intermediate portions, to somewhat diminish the divergence thereof. Fourth, the two end portions of the wire, at the lower ends of the members 14, are bent outwardly in opposite directions, in the plane of the hanger, to afford a pair of horizontally disposed arms 15 and 16. Fifth, the end portion of the wire, at the outer end of the arm 15, is bent downwardly, substantially in the plane of the hanger, and then folded outwardly upon itself in the same plane to afford a double prong 17.

Following this operation, the end portion of the wire at the upper end of the prong 17 is bent first transversely of the plane of the hanger and then downwardly to afford a single prong 18. The end portion of the single prong 18 is next folded upwardly onto the back of said prong, as indicated at 19. The two prongs 17 and 18 are in diverging relation transversely of the hanger, see Figs. 3 and 4. Sixth, the end portion of the wire, at the outer end of the arm 16, is bent downwardly, in substantially the plane of the hanger, and then folded upon its face to afford a double prong 20.

At the upper end of the double prong 20, the respective end portion of the wire is bent transversely of the hanger, in the opposite direction from the connecting member between the prongs 17 and 18, and then downwardly to afford a single prong 21. The end portion of the prong 21 is folded upon the back thereof, as indicated at 22. The prongs 20 and 21 are in diverging relation transversely of the hanger, see Fig. 7.

By reference to Fig. 1, it will be noted that the two pairs of prongs 17—18 and 20—21 are in diverging relation, see Fig. 1.

Relatively wide friction members 23, as shown rubber bands, are applied around the lower end portion of each double prong 17 and 20 and around the lower end portions of the single prongs 18 and 21 and their folded end portions 19 and 22.

The normal position of the hanger, below the sleeve 13, is shown by means of broken lines in Fig. 1.

A pair of pants x, only the bottom portions of which are illustrated, are held suspended from

the improved pants holder. Said pants are shown in section by means of broken lines in Figs. 1 and 3, and in full by means of broken lines in Fig. 2.

To attach a pair of pants to the hanger, the prongs, for instance 17 and 18, are inserted one in each of the open bottoms of the legs of said pants at the front creases therein. Next, the members 14 are contracted to draw the pairs of prongs 17-18 and 20-21 to shorten the distance therebetween and permit the prongs 20 and 21 to be inserted into the open bottoms of the legs of the pants. With the pairs of prongs 17-18 and 20-21 positioned in the legs of the pants, the contracting pressure on the members 14 is released to allow said prongs to yieldingly and internally engage the legs of the pants in their front and rear creases and thereby hold the same suspended from the hanger. It is, of course, evident that the prongs 17 and 21 are in one leg of the pants, and the prongs 18 and 20 are in the other leg thereof. The diverging pairs of prongs 17-18 and 20-21, which are held under tension by the legs of the pants, hold said legs from slipping from said prongs. Furthermore, the friction member or rubber bands 23 materially assist in holding the legs of the pants from slipping from the prongs 17-18 and 20-21.

In order to balance the improved hanger, it will be noted, and as heretofore stated, the double prongs 17 and 20 are on opposite sides of the 30 plane of the hanger.

From the above description, it is evident that the improved hanger will hold a pair of pants suspended therefrom without creasing or wrinkling the same. Furthermore, the weight of the pants held suspended from the improved hanger will tend to remove any wrinkles therein and keep the same in press.

To center the hook flatwise and the members of the pairs of prongs 17-18 and 20-21 relative to the plane of the hanger, the arms 15 and 16, which are directly connected to double prongs 17 and 21, respectively, are bent slightly oblique to the plane of the hanger, see Fig. 2.

What I claim is:

A hanger of the kind described made from a single piece of spring wire and comprising an up-standing hook, a pair of members depending from the shank of the hook in crossed arrangement transversely of the plane of the hanger and spaced apart in said plane, a pair of horizontally disposed arms projecting in opposite directions from the lower ends of said members, said arms being in outwardly diverging relation to said plane and on opposite sides thereof, and a pair of depending prongs on the outer end of each arm, the prongs of each pair being spaced apart transversely of said plane, the prong directly formed on the outer end of each arm being formed by a double thickness of the wire.

LEON H. ZEUTHEN.
